UNITED STATES PATENT OFFICE.

ALEXANDER C. PROUDFIT, OF BOSTON, MASSACHUSETTS.

DESIGN FOR AN ELECTRIC BICYCLE-LAMP.

SPECIFICATION forming part of Design No. 33,466, dated October 30, 1900.

Application filed October 2, 1899. Serial No. 732,422. Term of patent 14 years.

To all whom it may concern:

Be it known that I, ALEXANDER C. PROUDFIT, a citizen of the United States, residing at Boston, in the county of Suffolk and Commonwealth of Massachusetts, have invented and produced a new and original Design for Electric Bicycle-Lamps, of which the following is a specification.

The drawings show in Figure 1 in side elevation an electric bicycle-lamp in which my novel design is embodied, Fig. 2 showing the same in rear elevation.

The leading feature of my design for electric bicycle-lamps comprises a cylindrical body A, the length of which is but slightly in excess of the diameter and which has project-

ing about midway of its length a member in the form of a clamp B, substantially as illustrated.

Having fully described my design, what I claim, and desire to secure by Letters Patent, is—

The design for an electric bicycle-lamp, substantially as herein shown and described.

In testimony whereof I have signed my name to this specification in the presence of two subscribing witnesses.

ALEXANDER C. PROUDFIT.

Witnesses:

CHARLES M. THAYER,
WALTER E. J. KING.
